UNITED STATES PATENT OFFICE

JOHN N. HELTZEL, OF WARREN, OHIO

BRIDGING

Application filed July 2, 1927. Serial No. 203,110.

The present invention relates to bridging for wood and metal joists, concrete forms and other spaced members, and aims to provide such bridging composed of novel and 5 improved braces which are capable of withstanding both compression and tensile strains.

Another object of the invention is the provision of such braces formed from bars or strips of sheet metal in a novel manner, so 10 as to be inexpensive as well as practical and efficient.

A further object is the provision of bridging comprising crossed and pivoted braces which may be adjusted and readily 15 applied to the joists or other spaced members.

With the foregoing and other objects in view, which will be apparent as the description proceeds, the invention resides in the construction and arrangement of parts, as 20 hereinafter described and claimed, it being understood that changes can be made within the scope of what is claimed, without departing from the spirit of the invention.

The invention is illustrated in the accompanying drawing, wherein—

Figure 1 is a perspective view illustrating one of the bridges applied to metal joists of I-section.

Fig. 2 is a plan view of one of the blanks 30 from which the braces are formed.

Fig. 3 is a perspective view of the brace formed from the blank shown in Fig. 2.

Fig. 4 is an elevation of a bridge of modified form applied to metal joists of another 35 type.

Fig. 5 is an elevation of a modified bridge showing same disposed between and attached to wooden joists.

Fig. 6 is an elevation showing bridges of 40 modified form applied to the spaced boards or wall members of a concrete form, or the like.

Fig. 7 is a detail view illustrating a further modification.

Each bridge is composed of a pair of 45 crossed and pivoted braces, and each brace is formed from an elongated sheet metal blank, as seen in Fig. 2, which may be a bar or strip of metal. The blank which is bent 50 to produce the brace 11, is bent on parallel

oblique lines 12 whose ends extend to the opposite edges of the blank, with the inner end portions of the lines 12 in overlapping relation. The portions of the blank beyond the lines 12 are bent at right angles to the intermediate portion 13 between the lines 12, toward the same side. This produces, as seen in Fig. 3, the web 13 tapering to its ends, and the flanges 14 extending toward the same side from the web and increasing in width 60 toward their opposite ends, with the inner end portions of the flanges 12 in overlapping relation. The width of the web 13, between the lines or bends 12 is slightly narrower than the width of the blank, and the flanges 65 14 will stiffen the brace transversely so that the brace may receive considerable compression without bending or collapsing. The flanges 14 having their inner end portions in overlapping relation will strengthen the 70 brace at its central point. The brace has the flat terminal portions 15 extending beyond the ends of the flanges 14 or forming extensions of said flanges, and the flanges 14 have lugs 16 struck therefrom at the ends of the 75 web 13. The web 13 has an aperture 17 at the center of the brace between the inner end portions of the flanges 14.

Two of such braces are disposed back to back, and a rivet 18 or other pivot element 80 is secured through the registering apertures 17, thereby connecting the braces in crossed relation with the flanges 14 of the braces extending in opposite directions. This permits the braces to be swung relatively to one 85 another without interference. The bridge may thus be folded and the braces may be adjusted to different angles relatively to one another.

Fig. 1 illustrates a bridge applied to the 90 metal joists 19 of I-section. The terminal portions 15 extend across the flanges of the joists or beams 19 and are bent around the flanges at the opposite sides of the joists, to form hooks 20. The bridge thus prevents 95 separation of the joists and the braces will serve as tension members to resist separation of the joists. The lugs 16 contact with the flanges of the joists at the adjacent sides of said joists, and will therefore prevent the 100

joists from moving toward one another, so that the braces will serve as compression members. In this way, the braces will resist both compression and tension forces, and 5 will brace the joists securely in relative position.

The terminal portions 15 have apertures 21, as shown, to receive nails, screws or other securing elements when the braces are applied 10 to wooden joists or beams.

Fig. 4 illustrates a bridge of modified form as applied to joists 19^a having the T-heads 22 and the tubular bottom cords or members 23. The upper and lower terminal portions 15^a 15' extend across and are bent around the upper and lower portions of the joists to form hooks, as seen in Fig. 4, to resist separation of the joists, and the braces have the lugs 16^a contacting with the joists to take up the 20 compression strain between them.

Fig. 5 illustrates the terminal portions 15^b of the braces as being bent to bear against the adjacent sides of wooden joists 19^b, and fastened thereto by the nails or other securing 25 elements 24.

Fig. 6 illustrates the bridges as used for spacing the side boards or wall members 19^c of a concrete form or similar structure, the terminal portions 15^c of the braces extending 30 across the edges of the boards or members and being bent so as to hold said boards or members in relative spaced position.

Fig. 7 illustrates the terminal portion 15^d overlapping the abutting end portions of two 35 alining joists, with a pair of lugs 16^d, one engaging each joist, so that the bridge may serve as a joint for connecting the joists or maintaining them in alinement.

Having thus described the invention, what 40 is claimed as new is:—

1. A brace comprising flanges and a web between them, with the bends between the flanges and web arranged obliquely of the 45 brace, and the inner ends of the flanges being arranged close together.

2. A brace comprising flanges, a web between them, with the bends between the flanges and web arranged obliquely of the 50 brace, the inner ends of the flanges being arranged close together, and terminal portions extending from the opposite ends of said flanges beyond the ends of the web.

3. A brace comprising flanges, a web between them, with the bends between the flanges and web arranged obliquely of the 55 brace, the inner ends of the flanges being arranged close together, and terminal portions extending from the opposite ends of said flanges beyond the ends of the web, the flanges having lugs at the ends of the web.

4. A brace comprising flanges and a web between them, the web decreasing in width from its intermediate portion to its ends, and 60 the flanges increasing in width from the in-

termediate portion of the web to the opposite ends of the flanges.

5. A brace comprising flanges, a web between them, the web decreasing in width from its intermediate portion to its ends, and 70 the flanges increasing in width from the intermediate portion of the web to the opposite ends of the flanges, and terminal portions extending from the opposite ends of said flanges beyond the ends of the web. 75

6. A brace comprising flanges, a web between them, the web decreasing in width from its intermediate portion to its ends, and the flanges increasing in width from the intermediate portion of the web to the opposite 80 ends of the flanges, and terminal portions extending from the opposite ends of said flanges beyond the ends of the web, the flanges having lugs at the ends of the web.

7. A brace comprising an elongated sheet 85 metal blank bent on oblique lines extending to the opposite edges of the blank, and having a web between said lines decreasing in width from its intermediate portion to its ends, and having flanges beyond said lines 90 and increasing in width from the intermediate portion of the web to the ends of said web.

8. A brace comprising an elongated sheet metal blank bent on oblique lines extending to the opposite edges of the blank, and having a web between said lines decreasing in width from its intermediate portion to its ends, and having flanges beyond said lines 95 and increasing in width from the intermediate portion of the web to the ends of said web, the inner end portions of said flanges being in overlapping relation. 100

9. A brace comprising an elongated sheet metal blank bent on oblique lines extending to the opposite edges of the blank, and having a web between said lines decreasing in width from its intermediate portion to its ends, and having flanges beyond said lines 105 and increasing in width from the intermediate portion of the web to the ends of said web, and terminal portions extending from the opposite ends of said flanges beyond the ends of the web. 110

10. A brace comprising an elongated sheet metal blank bent on oblique lines extending to the opposite edges of the blank, and having a web between said lines decreasing in width from its intermediate portion to its ends, and having flanges beyond said lines and increasing in width from the intermediate portion 115 of the web to the ends of said web, and terminal portions extending from the opposite ends of said flanges beyond the ends of the web, said flanges having lugs at the ends of the web.

11. A brace formed from an elongated metal blank of substantially uniform width and bent along substantially parallel oblique lines to provide a web decreasing in width from its intermediate portion toward the 120

ends of the blank and flanges increasing in width from the intermediate portion of the web to the opposite ends thereof.

12. A brace formed from an elongated blank of substantially uniform width, the blank being bent on substantially parallel oblique lines having their adjacent end portions in overlapping relation and having their opposite ends terminating short of the ends of the blank, to form a web decreasing in width from its intermediate portion to the opposite ends of said lines and flanges increasing in width from the intermediate portion of the web to the ends thereof.

13. A bridge of the character described comprising a pair of braces each comprising flanges and a web between them, with the bends between the flanges and web arranged obliquely of the brace and the inner ends of the flanges being arranged close together, the webs of the braces being pivoted together at the inner ends of the flanges, and said flanges having lugs near the ends of the webs to engage spaced members, said flanges having bendable terminal portions projecting beyond said lugs.

14. A bridge of the character described comprising a pair of braces each comprising flanges and a web between them, with the bends between the flanges and web arranged obliquely of the brace and the inner ends of the flanges being arranged close together, the webs of the braces being pivoted together at the inner ends of the flanges, said flanges having portions at the ends of the webs to engage spaced members to receive both compression and tension forces.

15. A brace comprising flanges and a web between them, with the bends between the flanges and web arranged obliquely of the brace, and the inner ends of the flanges being arranged close together, said flanges having lugs at the ends of the web to engage spaced members, and said flanges having bendable terminal portions projecting beyond said lugs.

In testimony whereof I hereunto affix my signature.

JOHN N. HELTZEL.
